MEANS FOR LOOSENING A WINDOW SASH
FROM ITS FRAME

John Waldheim, Elizabeth, N. J.

Application April 4, 1936, Serial No. 72,723

18 Claims. (Cl. 254—131)

This invention relates to means and the method of loosening a window sash from its frame.

It is sometimes difficult to open a window due to the fact that the sash becomes jammed in a skewed position between the sides of the window frame, and also because the sash becomes joined to the frame due to painting. To loosen the sash in each instance generally requires considerable force and often causes great discomfort and sometimes injury to the palms of the hands by bumping them against the upper cross bar of the lower window sash. The loosening of the sash may be accomplished by a slight movement of the sash after which the sash may be moved with ease.

An object of the present invention is to provide a device in the form of a jack by which a comparatively small movement may be imparted to the sash with great pressure and a minimum of effort on the part of the operative, to loosen the sash from the frame so that it may be subsequently moved readily without the use of the jack to completely open the window.

Another object of the invention is to provide a jack for use on an ordinary plain window sash not provided with hand grips, notches or any other special devices to be engaged by the jack.

Still another object of the invention is to provide a jack which may also be used to lower the upper sash of the window as well as raise the lower sash.

Features and advantages will be apparent in the description of the accompanying drawings wherein—

Fig. 1 is an end elevation of the jack;

Fig. 2 is a side elevation of the jack as seen from the right of Fig. 1;

Fig. 3 is a view similar to Fig. 1 showing a shorter adjustable rod section thereon;

Fig. 4 shows a fragmentary portion of the jack in its actuated position.

Fig. 5 is a horizontal section taken on the line 5—5 of Fig. 2;

Fig. 6 is a diagrammatic view of the jack showing it in position to pry up the lower sash of a window;

Fig. 7 is a view, similar to a portion of Fig. 6, showing the jack in place to pry down the upper sash;

Fig. 8 is a sectional side view taken on the lines 8—8 of Fig. 6; and

Fig. 9 is a sectional side view taken on the line 9—9 of Fig. 7.

Similar reference characters represent similar parts throughout the several views.

The jack comprises two elements, namely a lever 15 and a rod or shaft 16 actuated thereby, the rod being composed, for a purpose herein-after described, of two sections, a base section 17, and an extension section 18.

The lever 15 consists of a handle 19 and a lobe or rocker-shaped portion 20 on which the lever may be actuated, by means of the handle 19, from the position, Fig. 1, to the position in Fig. 4, to actuate the rod 16 lengthwise. The lever 15 is provided with a circular portion 21, herein shown as concaved, engaging a convexed portion 22 formed on the lower end of the base section 17 of the rod 16.

The curved portion 21 forms with the rocker-like portion 20 a curved wedge-like member or cam 23 which, while the lever is being rocked on the lobe or curved fulcrum 20, to the position in Fig. 4, operates under the lower end of the rod 16 to push the latter upwardly and thus raise an object which may be engaged by the upper end 24 of said rod. The lever engages the rod 16 in a manner such that the pressure imparted to the rod is distributed substantially over the entire end of the rod, this being desirable for strength and wear. The operation of the jack may be facilitated by the use of a suitable lubricant to be applied where the lever engages the rod.

One of the uses of the jack, as above stated, is to pry a window sash loose from the window frame. For this purpose the jack may be placed as in Figs. 6 and 8 with the lever 15 engaging an object foreign to the jack such as the window sill 25, of a window frame 26, and the upper end 24 of the rod 16 engaging under the upper cross-bar 27, near one side thereof, of the lower sash 28. The lever 15 may then be actuated by swinging the handle 19 away from the rod 16, towards the opposite side of the sash, thus causing the curved wedge-shaped portion 23 to creep or work in under the lower end of the rod section 16, while the lever acts against the window sill 25, to increase the effective length of the jack and thus push the sash 28 upwardly. Only a slight movement of the sash is required to pry it loose. It will be understood that the active fulcrum portion of the lobe 20 of the lever 19 is always substantially under the rod section 17, see Figs. 1 and 4, thus making possible not only a uniform pressure, for all positions of the lever, but also maximum pressure is always applied thereby.

After the left hand side of the sash 28 has been loosened the jack may be placed at the opposite side of the window, as indicated in dot-

and-dash lines, Fig. 6, so that the rod 16 engages the sash bar 27 near its opposite side. The lever 15 may then be again operated, as before, to pry loose the right hand side of the sash. After the sash has been thus pried loose at both sides, it may readily be raised in the usual manner, without the use of the jack, to any desired position. The jack may be tilted slightly from a vertical position, as shown in dot-and-dash lines in Fig. 6, 10 when used at either side of the sash. This is done to have the upper end 24 of the rod 16 either vertically above the point of contact of the lobe 20 or slightly toward the lever side of the jack with reference to a vertical plane extending through said point of contact.

The jack of this invention may also be used, with equal facility, to lower the upper sash 30. For this purpose the jack is placed near one side of the sash 30, as in Figs. 7 and 9, with the lever 15 set on the lower cross bar 31 of the upper sash 30 so that it may readily be reached by the operator standing at the window. While the jack is in this position the upper end 24 of the rod 16 is caused to engage under the upper portion 25 or lintel 32 of the window frame 26 and the lever 15 is then operated, as above described in connection with the lower sash 20, thus pushing the sash 30 downwardly. This operation is subsequently repeated at the opposite side of the sash 30. After the sash 30 has been thus loosened at both sides it also may be manipulated readily without the use of the jack.

While lowering the upper sash 30 by means of the jack the lower cross-bar 31 of the upper sash 30 moves down behind the upper cross-bar 27 of the lower sash 28. Consequently the lever 15 moves down in the narrow space between the upper cross-bar 27 of the lower sash and the glass pane of the upper sash 30. Accordingly the lever 15 and the rod 16 are comparatively narrow to permit the jack to move down behind the cross-bar 27. The lever is also cut away at 19c Fig. 2, so that the handle may extend slightly diagonally over the upper cross-bar 27 towards the operator while the lobe 20 extends down behind said cross bar 27.

To prevent scratching of the window frame and the sash the lobe or fulcrum portion 20 of the lever may be provided with a piece 33 of any kind of non-abrasive material as for example leather or rubber, and the upper end 24 of the rod 16 is capped with a portion 34 of the same kind of non-abrasive material. These portions 33 and 34 may be secured to the lever 15 and rod 16 respectively in any suitable manner as for example by nails 35 and 36, the lever 15 and rod 16 being preferably composed of wood although they may be composed of metal.

The lever 15 is preferably attached to the rod 16 to form a unitary structure. To this end said lever is provided with a projection 37 herein shown as a staple which is driven into the lever so that its loop end 38 is substantially concentric with the center of curvature of the curved portion 65 21 of the lever. The staple 37 engages in a narrow, upwardly extending slot 39 in the lower end of the rod 16, and a pin 40 extends through the two ears 41, formed on the rod, by the slot 39, and through the loop 38 of the staple 37. The staple 70 37 fits around the pin 40 loosely and does not aid in keeping the rod 16 properly positioned lengthwise of the lever, this being accomplished by the socket or groove 21, in which the rod engages. The staple 37 does, however, prevent displacement of the rod 16 transversely of the lever 15

because it fits into the slot 39 of said rod. The looseness between the loop 38 of the staple 37 and the pin 40 permits the lever 15 to be swung close to the rod section 17, as in Fig. 3, for convenience in storing the jack while not in use.

The heights of window sashes vary from small dimensions of pantry windows to larger dimensions of bath room windows and to still larger dimensions of living room windows. Accordingly provision is made to vary the length of the jack. 10 For this purpose the rod 16 is composed of the two sections 17 and 18, as previously stated, the extension section 18 being settable up or down on the base section 17, in various positions, in accordance with the desired length of the jack. The 15 sections 17 and 18 are provided with teeth 41 and 42 respectively which constitutes interlocking means to prevent the extension section 18 from slipping down on the base section 17 while the jack is under pressure.

To hold the extension rod section 18 against the base section 17 and thus maintain the teeth 42 in engagement with the teeth 41 suitable means may be provided, herein shown as a clamp, indicated generally by the numeral 43. Said 25 clamp consists of a U-shaped frame 44, composed of sheet metal and comprising two side plates 45 bent up from a transverse portion 46, see Figs. 2 and 5, so as to fit around the upper end of the rod section 17 to which the frame 44 is secured by 30 nails 47 extending through the portion 46 of said frame and driven into the rod section 17. A member 48 is located between and is secured to the free ends of the side plates 45. Said member has cooperating therewith a cam 49 herein shown 35 as pivotally supported by said member or pin 48 so that as the cam is swung about the pin 48 to the full line position in Fig. 2, by a finger piece 50, it presses the rod section 18 against the rod section 17 and holds it there. It will be understood that the engaging faces of the teeth 41 and 42 extend at right angles to the direction of pressure of the rod sections 17 and 18. Consequently there is no force or pressure against the cam 49 or its pivot 48 effected by the thrust action of the rod. Consequently there is no danger of accidentally opening or injuring the clamp while pressure is exerted on the rod 16.

When the clamp is to be released, to permit the length of the jack to be changed, the cam 49 is 50 swung upwardly about the pivot 48, to the dot-and-dash line position in Fig. 2. The extension section 18 may then be actuated about the upper end of the base section 17, to the position shown in dot-and-dash lines in Fig. 2, to disengage the teeth 42 from the teeth 41. Subsequently the extension section 18 may be moved up or down, on the base section 17, in accordance with the desired length of the jack. The jack section 17 has at its upper end a flat face 51 on which the teeth 60 42 may slide so that the up or down movements of the extension section 18 may be free and without hinderance by the teeth 41. After the extension section has been adjusted to the desired length of the jack it may be swung back against the section 16 and then be claimed in place, as above described, by the clamp 43. It will be understood that the cam 49 may be disposed as in Fig. 3, in its clamping position, so as to be swung downwardly by the handle 50 during the release- 70 75 operation of the clamp.

To provide the proper distance of the pin 48 from the rod section 18 so that the cam may properly engage the rod section 17 and that the finger piece 50 shall not be too close to said rod 75

section in the clamping position of the cam, one or more wedges 52 are provided. These wedges are located between the rod section 17 and the portion 46 of the clamp frame 44 and may be 5 adjusted relatively to each other to procure the desired distance of the pin 48 from the rod section 17. Subsequently the nails 47 are driven through said wedges and hold them in place.

The extension section 18 has a definite length 10 and is shown, by full lines, in its minimum adjustment, which makes the jack twenty six inches long as indicated by a scale 53 on the rod section 18, and a pointer 54 on the rod section 17. The length of the jack may be increased to thirty five 15 inches by extending the section 18 upwardly to the position indicated in dot-and-dash lines.

If the jack is to be used for a window sash smaller than the range of adjustment of the rod section 18, the latter may be readily removed and 20 substituted by a smaller section 18^x, Fig. 3, the latter having a scale 53^x by which it may be set to various positions to alter the length of the jack within the range of sixteen inches to twenty five inches. It will be understood that the jack 25 may also be gauged if desired by placing it on the window sill and then pulling the extension rod section upwardly until it engages under the upper cross-bar 27 of the sash.

Occasionally the sash sticks in a slightly open 30 position. Should this happen to the lower sash the jack may be used to push the sash towards its closed position by operating the lever after it has been placed on the upper cross-bar of the lower sash and while the upper end of the rod 35 engages the lintle. Similarly the upper sash may be pushed towards its closed position by operating the lever against the window sill while the upper end of the rod engages the lower cross-bar of the upper sash.

From the foregoing it will be understood that 40 the jack of this invention comprises two elements, namely, a lifting rod 16 and a lever 15 of the first order to engage under the lower end of said rod, said lever having a fulcrum portion 20 on its edge by which the rod is actuated axially; that said rod has a curved base portion 22 and the lever has a curved portion 21 conforming to the shape of the curved base portion to engage the latter; that said curved portions 21 and 22 50 cooperate with each other to prevent slipping of one of said elements out of engagement with the other element during the operation of the jack.

It will also be understood that in the present 55 invention the curved portion 21 of the lever is in the form of a socket and that it forms with the curved face of the bearing portion 20 of said lever a wedge-like portion or cam 23 which creeps under one end of the rod to move the latter axially while the lever is being actuated.

It will further be understood that one of the 60 jack elements 15, 16 has a slot 39 therein forming two ears 41, that the other element has a projection 37, herein shown as a staple, extending into said slot, and that a pin 40 extends through said ears 41 and through the aperture of said projection, or, in other words, the loop 38 of the staple, to prevent accidental displacement of the rod transversely of the lever and to keep said concaved portion 21 and said convexed portion 22 70 within cooperative range of each other, that the staple 38 and pin 40 provide a means for connecting the lever with the rod to form a unitary structure, and that the lever engages beneath the rod to actuate it independently of this connecting means.

It will be further understood that the lever 15 and the rod 16 are of substantially the same width and sufficiently narrow so that the jack may be set on the lower cross bar of the upper sash of a window when the upper sash of the window is to be lowered and may move downwardly behind the upper cross bar of the lower sash while the upper sash is being lowered, and that the upper end of the rod bears against the lintle of the window frame during the lowering 10 operation of the upper sash.

It should also be understood that the rod 16 of the jack is composed of two sections 17 and 18, that the lever 15 engages the lower end of one of said sections to actuate the rod in the direction 15 of its length, that said sections 17 and 18 overlap each other, that one of said sections is adjustable lengthwise of the other to alter the length of the rod, that there are interlocking means, herein shown as teeth 41 and 42, between the overlapping portions of the rod sections to prevent slipping of the adjustable section 18 on the other section 17 when pressure is applied to said rod by said lever, and that the adjustable or extension section 18 is held against the other section by the clamping means 43 to keep the teeth 41 and 42 in engagement with each other.

It will also be understood that the clamping means 43 is supported on said lever engaged section 17 of said rod and includes two side plates 30 45 extending from the lever engaged section, an element or cam 49 between said plates, and a member or pivot 48, supported by the free end of said plates, with which said cam cooperates, that said adjustable section 18 is guided between the two side plates 45, that said cam engages the adjustable section to hold it against the other section to prevent said teeth from slipping out of engagement with each other, and that there is 35 provided an inclined toothless surface 51 at the upper end of the toothed side of the base rod section 17 against which the extension section may be swung to disengage its teeth from those of the base section and on which toothless surface the extension section 18 may be slid freely up or 45 down to prevent a collision of the teeth 41 with the teeth 42 while changing the length of the rod 16, and that the distance between said member 48 and nearest face of the adjustable rod section may be regulated so that the cooperating 50 element or cam may properly engage the adjustable rod section 18.

While certain preferred embodiments of the 55 invention have been shown and described, it will be understood that changes in the form, arrangements, proportions, sizes and details thereof may be made without departing from the scope of the invention as defined in the appended claims.

I claim:

1. In a jack, the combination of two elements, namely a lifting rod, and a lever to actuate said rod, said rod having a curved bottom end, said lever having a curved portion extending under said rod, the curved portion of said lever conforming to the shape of the curved bottom end to engage the latter, said lever having also a curved bearing section adapted to engage an object foreign to said jack for the purpose of rocking the lever and thus causing it to push said 70 rod, the curved bottom end of said rod and the curved portion of said lever cooperating with each other to prevent slipping of one of said elements out of engagement with the other element during the operation of the jack, said lever 75

- being of the first order so that the movement of the rod is produced by a movement in the opposite direction of the handle part of the lever.
2. A jack comprising only two elements, namely a lever, and a lifting rod to be actuated thereby, cooperative portions one on each of said elements, one of said cooperative portions being a curved socket, the other cooperative portion being convexed to fit into said socket, a curved fulcrum hump on said lever to form a cam with the cooperative portion of said lever, and on which hump the lever may be rocked to cause the cam to work under said rod to operate it lengthwise of itself, one of said elements having a slot therein forming two ears, the other element having a projection extending into said slot, said projection having an aperture, and a pin extending through said ears and through the aperture of said projection to prevent accidental detachment of the handle from the rod and to keep said socket and said convexed portion within cooperative range of each other.
3. A jack comprising only elements, namely a lifting rod, and a lever to actuate said rod, said lever having a curved portion to engage beneath the base of the rod, a fulcrum hump on said lever about which it may be actuated to cause the curved portion to cooperate with said base to actuate said rod, and guiding means carried by one of said elements and cooperating with the other element to prevent the rod from slipping from the lever transversely thereof, said lever being of the first order so that the movement of the rod is produced by a movement in the opposite direction of the handle part of the lever.
4. In a jack, the combination of a rod including two sections, a lever to engage the lower end of one of said sections to actuate the rod in the direction of its length, said sections overlapping each other, one of said sections being adjustable lengthwise of the other to alter the length of the rod, clamping means supported on and at the upper end of the lever engaged section of said rod, the adjustable section being guided by the clamping means only, and teeth on both sections to engage each other to prevent slipping of one section relatively to the other section while the jack is under pressure, said clamping means including a member to engage the adjustable section to hold it against the other section to prevent said teeth from slipping out of engagement with each other.
5. In a jack, the combination of a rod including two sections, a lever to engage the lower end of one of said sections to actuate the rod in the direction of its length, said sections overlapping each other, one of said sections being adjustable lengthwise of the other to alter the length of the rod, clamping means on said lever engaged section of said rod, the adjustable section being guided by the clamping means, and teeth on both sections to engage each other to prevent slipping of one section relatively to the other section while the jack is under pressure, said clamping means including a member to engage the adjustable section to hold it against the other section to prevent said teeth from slipping out of engagement with each other, said member being settable to another position without removing it from the jack to permit the adjustable section to be moved away from the other section to disengage the teeth and thus permit the adjustable section to be set to another position lengthwise of the other section to vary the length of the jack.
- 75 6. In a jack, the combination of a rod includ-

ing two sections, namely a base section, and an extension section, clamping means on the base section to secure the extension section to said base section, said extension section being detachable so that it may be substituted by another one of different length while the clamping means remains on the base section, said clamping means serving also to guide the extension section onto the base section.

7. In a device for loosening a window sash from its frame, the combination of a lever having a fulcrum portion to engage directly with a window sill, and a rod extending from said lever to the upper cross bar of the lower sash, said lever engaging the lower end of said rod to push it upwardly and thus move the sash in the same direction, said lever and said rod being narrow and of substantially the same width so that the device may be set on the lower cross bar of the upper sash when the upper sash is to be lowered and so that a portion of the device may move downwardly behind the upper cross bar of the lower sash while the upper sash is being lowered, the upper end of the rod bearing against the lintel of the window frame during the actuation of the lever while lowering the upper sash.

8. In a jack, the combination of a rod, and a lever to engage one end of said rod, said lever having a rocker-like portion at one end adapted to engage the surface of an object foreign to the jack, and a handle at the other end thereof, said lever being operable by a movement of said handle to rock the lever by its rocker-like portion upon the foreign object to thereby move the rod axially, said lever having its active fulcrum substantially under said rod to produce always a substantially uniform and maximum pressure on said rod.

9. In a jack, the combination of a rod, a lever, said lever having a rocker-like portion at one end to engage the surface of an object foreign to said jack, and a handle at the other end thereof, said lever being of the first order and operable by a movement of said handle to rock the lever upon its rocker-like portion to thereby move the rod axially, and means connecting the rocker-like portion of the lever with the end of said rod, the lever engaging beneath the end of the rod to actuate said rod independently of the connecting means, said lever having its active fulcrum substantially under said rod to produce always a substantially uniform and maximum pressure on said rod.

10. In a jack, the combination of two elements namely a rod, and a lever to engage one end of the rod to push the latter axially, one of said elements having a depression in which the other element engages, one of said elements having a slot in the end thereof, a staple on the other element, said staple extending into the slot of the other element, and a pin on the last mentioned element extending through said staple.

11. In a jack, the combination of a rod including two sections, a lever to engage the lower end of one of said sections to actuate the rod in the direction of its length, said sections overlapping each other, one said sections being adjustable lengthwise of the other to alter the length of the rod, clamping means on the lever engaged section of said rod, said clamping means including two side plates extending from the lever engaged section, a member extending from one to the other of said side plates, an element located between said side plates and cooperating with said member to press the adjustable rod section

against the lever engaged rod section, and interlocking means between said rod sections.

12. In a jack, the combination of two elements, namely a rod, and a lever to engage the end of said rod to actuate the latter, one of said elements having a slot therein to form two members, a staple on the other element extending into said slot, and a pin extending through said members and through the loop of said staple.

13. In a jack, the combination of a lifting rod, and means to actuate it axially, said rod comprising two sections namely a base section and an extension section, teeth on each rod section to cooperate with each other to prevent slipping of the extension section on the base section while the rod is under pressure, means to hold the extension section against the base section, and a toothless portion at the upper end of the toothed side of the base section against which the extension section may be swung to disengage its teeth from those of the base section and on which toothless portion the extension section may be slid freely up or down while changing the length of the jack.

14. In a jack, the combination of a rod, and a lever, said lever having a curved wedge-like portion to engage said rod and gradually creep under one end of it to move the rod axially while the lever is being actuated, the active fulcrum of said lever being always substantially under said rod.

15. In a jack, the combination of a load engaging rod, and a lever to actuate said rod, said rod having a curved surface at its lower end, said lever having a curved portion conforming to the shape of said curved surface and which said lower end engages, said lever having also a curved fulcrum surface to engage an object foreign to the jack and upon which said lever may be rocked, the center of curvature of the rod engaging surface being so disposed with respect to the center of curvature of the fulcrum surface as to form a cam at one end of the lever whereby the rod may be actuated.

16. In a window jack, the combination of a

lever, and a rod operable by said lever, said jack being of sufficient length to reach from the lower cross bar of an upper window sash to the lintel of the window frame, said jack being also sufficiently narrow to pass freely between the upper cross bar of the lower sash and the window pane of the upper sash while the upper sash is being lowered by the jack, said lever having a fulcrum lobe thereon to engage the lower cross bar of the upper sash, and a handle extending from said lobe, said handle being positioned with respect to said lobe that it may extend slightly diagonally over the upper cross bar of the lower sash while the lobe extends down behind said upper cross bar.

17. In a jack, the combination of two elements, namely a lifting rod, and a lever to actuate said rod, said rod having a curved bottom end, said lever having a curved portion conforming to the shape of said curved bottom end to cooperate therewith to maintain engagement between the lifting rod and the lever, said lever also having a curved bearing section adapted to rock on an object and push said lifting rod away from the object engaged by said curved bearing section of said lever, said curved bottom end of the lifting rod and said curved portion of the lever cooperating therewith being so shaped as to maintain the lower end of the lifting rod substantially over the area of contact between the curved bearing section of the lever and the object on which it bears.

18. A jack including two elements namely, a lever, and a lifting rod to be actuated by said lever, cooperative portions one on each of said elements, one of said cooperative portions being a curved socket, the other cooperative portion being convexed to fit into said socket, and a curved fulcrum hump on said lever to form a cam with the cooperative portion of said lever, and on which hump the lever may be rocked to cause the cam to work under said rod to operate it lengthwise of itself.

JOHN WALDHEIM. 45
